his Attorney.

UNITED STATES PATENT OFFICE.

GUSTAV OESS, OF ESSEN, GERMANY.

CONSTRUCTION OF TRACKS OF STREET RAILWAYS.

Application filed March 7, 1928, Serial No. 259,681, and in Germany March 19, 1927.

My invention relates to improvements in the construction of tracks of street railways, and more particularly to tracks in which blocks of concrete located alongside the rails and at both sides thereof, are provided, which blocks are rigidly connected with the rails into a coherent body. The object of the improvements is to provide a track of this type which can be manufactured at low cost, and which is constructed so that it does not injure the road-bed. With this object in view my invention consists in providing elongated reinforcing members of concrete or the like alongside both sides of each rail, which are rigidly connected with the rail to provide an independent body adapted to be placed on the road-bed from the surface thereof, the reinforcing members extending at their top sides to the surface of the road-bed, and the combined rail and reinforcing members being capable of oscillation under the weight of the cars independently of the road-bed. The said oscillations are not interfered with by the road-bed, so that the said road-bed is not destroyed by the said oscillations. In order to reduce the cost of the combined rail, the reinforcing bodies of concrete or the like are secured to the rail located between the same by means of yokes passed below the foot of the rail and having upwardly projecting ends embedded in the reinforcing members.

In order that my invention may be more clearly understood, two examples embodying the same have been shown in the accompanying drawing, in which

Fig. 1, is a sectional elevation showing the combined rail, and

Fig. 2, is a similar sectional elevation showing a modification.

In the example shown in Fig. 1 at both sides of the rail *a* elongated members *b* and *c* of concrete are provided, which either extend to the surface of the road-bed, or to a part near the said surface, in which case the members are coated by a layer *k* of asphalt or the like. The member *b* and *c* are rigidly connected with the rail *a* by means of yokes *d* disposed below the foot of the rail and having their ends *e*, *f* bent upwardly and into the body of the members *b* and *c*. The yokes are fixed to the rail by means of clamping plates *g* engaging the top face of the foot of the rail and clamped

into engagement therewith by means of bolts *o*.

The modification shown in Fig. 2 is similar to the one illustrated in Fig. 1, and the same letters of reference have been used to indicate corresponding parts. But the yokes *d*¹ are constructed in a different way. As shown in the said figure the upwardly bent ends *m* of the yokes *d*¹ are bent around reinforcing bars *n* embedded in the members *b* and *c* and they are fixed in position either by stamping or casting concrete around the same.

In both examples the bottom faces of the members *b* and *c* are inclined downwardly from the web of the rail and outwardly, so that the material of the roadbed is pressed together below the rail and forced to the middle thereof.

I claim:

1. In a track, a rail, a pair of reinforcing blocks located alongside said rail at opposite sides thereof and each block extending with its top face to the surface of the road, and means passing under the rail for securing said reinforcing blocks to said rail, the combined rail and blocks providing a beam capable of oscillation independently of the roadbed.

2. In a track, a rail, a pair of reinforcing blocks located alongside said rail at opposite sides thereof and each block extending with its top face to the surface of the road, and yokes passed below the foot of the rail and in engagement with said blocks for fixing said blocks to the rail, the combined rail and blocks providing a beam capable of oscillation independently of the road-bed.

3. In a track, a rail, a pair of reinforcing blocks located alongside said rail at opposite sides thereof and each block extending with its top face to the surface of the road, anchoring members within said block, and yokes passed below the foot of said rail and connected to said anchoring members for securing said blocks to said rail, the combined rail and blocks providing a beam capable of oscillation independently of the road-bed.

4. In a track, a rail, a pair of reinforcing blocks located alongside said rail at opposite sides thereof and each block extending with its top face to the surface of the road, yokes passed below the foot of the rail and in engagement with said blocks for fixing

said blocks to the rail, and clamping members in position for clamping said yokes to the foot of the rail, the combined rail and blocks providing a beam capable of oscillation independently of the road-bed.

5. In a track, a rail, a pair of reinforcing blocks located alongside said rail at opposite sides thereof and each block extending with its top face to the surface of the road,
10 said blocks extending with their side faces

beyond the foot of the rail and having their bottom faces inclined downwardly and outwardly, and means for securing said reinforcing blocks to said rail, the combined rail and blocks providing a beam capable of oscillation independently of the road-bed.

15 In testimony whereof I hereunto affix my signature.

GUSTAV OESS.
